United States Patent Office

Des. 175,255
Patented Aug. 2, 1955

175,255

HANDBAG

William H. Hardy, River Edge, N. J.

Application December 3, 1954, Serial No. 33,379

Term of patent 7 years

(Cl. D87—3)

Fig. 1

Fig. 2

Fig. 3

Fig. 4

Fig. 5

Fig. 1 is a front elevational view of a handbag showing my new design;

Fig. 2 is a side view thereof;

Fig. 3 is a top view of the handbag;

Fig. 4 is a rear view thereof; and

Fig. 5 is an open view of the handbag.

I claim:

The ornamental design for a handbag, substantially as shown.
